CLAMSHELL ASSEMBLY

BACKGROUND OF THE INVENTION

1. Field of the Invention

The invention pertains to clamshell buckets.

2. Description of the Prior Art

The commercially employed clamshell buckets which were used prior to the present invention employed two hydraulic cylinders, with each cylinder being used for each bucket of the clamshell. The present invention eliminates one of the cylinders and obtains movement of both buckets by interconnecting the buckets through a linkage.

Also, the clamshell buckets employed commercially prior to the present invention were usually not rotatably mounted to the boom of the back hoe or similar construction equipment.

In some instances in which rotational mounting was provided, the mounting structure was quite complicated and expensive. The present invention eliminates the cumbersome prior art structures.

SUMMARY OF THE INVENTION

The primary object of the present invention is to provide an extremely versatile clamshell bucket without employing complicated or cumbersome mechanisms.

DESCRIPTION OF THE DRAWINGS

FIG. 1 is a side plan view of the clamshell bucket embodying the present invention;

FIG. 2 is a top plan view thereof;

FIG. 3 is a side plan view taken on line 3-3; and

FIG. 4 is a diagrammatic view of the mechanism employed to rotate the clamshell assembly in respect to the boom.

DESCRIPTION OF THE PREFERRED EMBODIMENT

The major components of the clamshell bucket embodying the present invention are a sprocket wheel assembly 10 which is fixedly connected to a boom (not shown) of the back hoe, a frame 12 which is mounted for rotation around the sprocket wheel assembly, jaws 14 and 16 which are pivotally mounted at the lower end of the frame, a double-acting hydraulic cylinder 18 for closing and opening of the jaws, and two hydraulic cylinders 20 and 22 which are operable to rotate the frame in respect to the sprocket wheel assembly.

The sprocket wheel assembly 10 is comprised of an eye member 24 and two key members 25 and 26 all of which are welded to a supporting member 27. These elements serve to fix the sprocket assembly to the boom, and in themselves do not form an essential part of the present invention. A sprocket wheel 28 is welded to the lower face of the supporting member and a threaded shaft 29, which is also fixed to the supporting member 27, projects through a bushing 30 which is fixed in the top plate 31 of the frame 12. The sprocket wheel assembly 10 is secured to the frame 12 via a bearing plate 32 which is mounted on the lower projecting portion of the shaft 29. The frame, although being secured to the sprocket wheel assembly, is free to rotate in a horizontal plane in respect thereto.

The frame 12 has two downwardly extending legs 34, 34 each of which are fixed to the top plate 31 and terminate at two spaced-apart bushings 36 which receive the right- and left-hand jaw pivot pins 38 and 39. The hydraulic cylinder 18 is bolted to the inside faces of the legs 34 and is free to pivot around its mounting pin 40. The ram of the cylinder 18 is pivotally connected by pin 41 to two upwardly extending flanges 42 of the jaw 14. The flanges 42 extend further inwardly towards the center of the clamshell bucket and are pivotally connected by pin 43 to link 44 which in turn is connected to two upstanding flanges 46 of jaw 16 by pin 45. A jaw-scraper assembly, which is comprised of a rectangular

frame 47, is positioned inside the jaws and is connected on both of its sides to pins 39 and 38 by eye members 48.

As the cylinder is retracted from the position shown in FIG. 1, it causes jaw 14 to pivot in a counterclockwise direction around pin 38. Simultaneously, link 44 imparts an equal clockwise motion to jaw 16 as it pivots around pin 39. During the movement of jaws 14 and 16, the jaw-scraper assembly remains stationary in respect to the frame 12 and thereby causes the frame 47 to scrape along the sides and bottoms of the jaws.

The hydraulic cylinders 20 and 22 are fixed within channel sections 50, 50 which are welded to the upper ends of the frame legs 34. The piston of each of these cylinders carries a small horizontally disposed sprocket wheel 51 which is engaged by a chain 52. The chain is anchored at both of its ends to lugs 53 which are fixed to the channel sections 50. The chain extends partially around the small sprocket wheels 51 as well as around the sprocket wheel 28 of the fixed sprocket wheel assembly 10. A second chain 54 is fixed at both of its ends to tabs 55, which are fixed to the pistons of cylinders 20 and 22, and extends around horizontally positioned sprocket wheels 56, 56 which are fixed within a channel section 58 which is connected at both of its ends to channel sections 50, 50.

The above-described arrangement of the sprocket wheels and chains 52 and 54 permits unlimited turning of the clamshell assembly through 90° and assures positive engagement between chain 52 and the sprocket wheel 28. To rotate the clamshell assembly in a clockwise direction from the position shown in FIG. 2, the piston of cylinder 22 is retracted and simultaneously the piston of cylinder 20 is extended. Because the pistons of both cylinders are interconnected by chain 54, equal travel of both pistons is assured and thus slackening or disengagement of the chain 52 from sprocket wheel 28 is impossible.

Although but a single embodiment of the present invention has been illustrated and described, it will be apparent to those skilled in the art that various changes and modifications may be made therein without departing from the spirit of the invention or from the scope of the appended claims.

I claim:

1. A clamshell assembly having:
a frame with jaw means pivotally attached thereto and having means including a support member adapted to attach the clamshell assembly to the boom of a construction machine, said attachment means comprising;
a main sprocket wheel and means for fixedly attaching said main sprocket wheel to the support member;
bearing means connecting said frame to said main sprocket wheel for rotational movement in a horizontal plane in respect thereto;
two hydraulic cylinders fixed to said frame at opposing sides of said main sprocket wheel and each of said cylinders being provided with a separate sprocket wheel which is attached to the respective pistons of the cylinders; and
a chain fixed at both of its ends to said frame and extending over and engaging the sprocket wheels of said cylinders and under the main sprocket wheel therebetween to cause rotation of said frame in respect to said main sprocket wheel upon outward movement of one of said cylinders and simultaneous inward movement of the other of said cylinders.

2. A clamshell assembly and attaching means according to claim 1 wherein said pistons of said two cylinders are interconnected by means assuring simultaneous and equal speed of movement of said two pistons.

3. A clamshell assembly and attaching means according to claim 2 wherein said interconnecting means is comprised of two sprocket wheels which are fixed to said frame and a chain which engages said last-mentioned sprocket wheels and which is fixed at each of its ends to said pistons of said two cylinders.
